UNITED STATES PATENT OFFICE.

JOSEPH SCHNEIBLE, OF CHICAGO, ILLINOIS.

ROTARY PUMP.

1,116,851.

Specification of Letters Patent. Patented Nov. 10, 1914.

Application filed March 3, 1914. Serial No. 822,110.

To all whom it may concern:

Be it known that I, JOSEPH SCHNEIBLE, a citizen of the United States, residing at Chicago, in the county of Cook and State 5 of Illinois, have invented a new and useful Improvement in Rotary Pumps, of which the following is a specification.

My invention relates to an improvement in the class of rotary pumps, wherein centrifugal force is generated to overcome the head against which the pump operates.

In the accompanying drawing, Figure 1 illustrates my invention in a preferred form of its embodiment by a view in side elevation, with one head of the pump removed, the view showing parts in section and a part of the casing broken away to present the exit-port, shown in section; and Fig. 2 is a section on line 2, Fig. 1.

The pump-casing, provided with feet through which to bolt it to a stable foundation, is shown to be formed of a head 3 having a wall 4 extending from it to describe about its interior a complete true circle and 25 form the pump-chamber 5. This head has a central entrance-chamber 6 and affords a bearing for a rotatable shaft 7 to be coupled, for driving it, to a suitable prime mover (not shown). A head 8, closing the 30 chamber, is bolted to a flange about the chamber-wall and has a central hub-portion shown to be provided with a stuffing-box and affording another bearing for the shaft. On the shaft is secured a rotor 9, shown to 35 be composed of two opposite radially-extending blades, though the number thereof employed may exceed two if desired. Each blade is preferably formed of a plurality of hard-rolled spring metal sheets laminated 40 in successively increasing lengths and shown to be suitably secured at their inner ends (Fig. 1) to the opposite hub-members, which are bolted together to form a rigid hub 10, keyed to the shaft; the bolts passing through 45 the blades near their inner ends to secure the metal sheets in the laminated relation in which they are clamped between the hub-members. This construction of the rotor renders its blades, for the purpose herein- 50 after explained, resiliently yielding toward their tip-ends. The fluid to be pumped enters the chamber through the entrance-port 6, by way of a passage leading thereto and shown by dotted lines at 11 in Fig. 1 and

guiding the entrance of the fluid in the direction of rotation of the rotor. In practice it is found desirable to construct the width of the rotor tips to conform to the diameter of the suction-inlet 11 serving to convey the desired quantity of fluid to the pump (at 60 a normal rate of speed, which is approximately 3-4 feet per second in the case of water). It is preferred to provide only one exit-port 12, as shown, centrally in the wall 4. The port may be of any desired sectional 65 shape, though the shape of the throat found in practice to be the most desirable is round, which shape shows as an oval at the inner circular surface of the pump-chamber, the extent of elongation of the oval depending 70 on the angle of declination at which the port leads from the pump-chamber. The area of the throat of the exit-port, from which it enlarges outwardly toward the connecting part for the delivery pipe at its outer end, 75 is calculated, for water as the fluid to be pumped, to give a velocity of 50 to 75 per cent. of the rotor-tip velocity when the pump is operating under normal conditions.

In operation, the speed of the radial outward movement of the fluid under the action of the revolving rotor is materially reduced in its course from the intake to the rotor-tips; and the fluid which fills the annular space between the circle described by the extremities of the rotor-tips and the truly circular inner periphery of the casing, is beyond the rotating action of the blades, and is revolved by its own momentum while being at the same time subjected to a constant 80 radial pressure of the fluid which is being produced and maintained by the rotor in the pump-chamber. The pressure for discharging the fluid from the pump-chamber through the exit-port 12, therefore, is that 85 produced by centrifugal and velocity force within the chamber, instead of being produced, as heretofore, by converting velocity-force into pressure as the fluid leaves the impeller. The area of the throat of the exit-port should be less than the radial cross-sectional area of the annular space, as shown. Moreover, the capacity of the pump-chamber is such as to cause the rate of radial 90 flow therein to constantly decrease in the outward direction, so that the transition of the fluid, from the tip of the rotor to the annular space, takes place without eddy-

- currents, and being thence revolved within a perfectly circular guidance, the peripheral-velocity momentum of the slowly outwardly moving fluid is practically maintained. As will be understood, the pressure in the pump-chamber being radial and the velocity-pressure in the exit being tangential, the resultant force forms the angle of discharge of 45 degrees.
- 10 The annular space between the circle described by the revolving extremities of the rotor-tips and the inner circular circumference of the pump-chamber affords a species of reservoir for a supply of the fluid under pressure, which pressure is maintained throughout the operation by the constriction in the exit-port 12 which causes the discharging fluid to flow uniformly and smoothly and without impingement within it. The pressure at the throat, because of the velocity there, is less than at the inlet-end, so that the loss of pressure is, according to the well-known Venturi theory, substantially regained at the outlet end of the discharge-port, due to the decrease of velocity after the water passes the throat.
- Where a rigid rotor is used in my improved pump, the space referred to between the circle described by the extremities of the 30 rotor-tips and the inner circular periphery of the pump-chamber should be sufficiently large to prevent eddy-currents. When, however, the rotor-blades are resiliently yielding, as described, the tips will automatically adjust themselves to the discharge condition, and this space may be normally relatively small. These blades are sufficiently rigid, throughout their length, to resist flexing in overcoming the load within 40 the pump-chamber when the pump is operating under normal conditions. Should the normal head against which the pump is working be lowered, however, as by drawing off from a lower point in the line of discharge, causing the quantity of fluid passing through the pump to increase, the rotor with inflexible blades would increase the power-consumption and might detrimentally affect the pumping efficiency. With 50 the resiliently-bladed rotor in use under these conditions, the blades will adjust themselves thereto by flexing backwardly under the abnormal discharge-conditions and thereby increase the capacity of the aforementioned annular space by radially shortening the rotor-blades and prevent eddy-currents, but as the higher head is restored, the normal centrifugal force within the pump-chamber is regained and the blades will 60 straighten and operate the pump to deliver the fluid against the normal head. As will be seen, the flexible rotor-blades are capable of thus automatically adjusting themselves throughout a considerable range of variation 65 in head, from the maximum of head down-

wardly, by narrowing the circle through which the tip-extremities travel, which occurs whenever an excessive quantity of fluid is discharging through the contracted exit-port 12.

The gist of the invention lies in allowing the annular space between the circle described by the extremities of the revolving rotor-tips and the completely circular circumferential inner surface of the pump-chamber, whereby radial pressure generated in the pump is supplied and maintained on the fluid while it is discharging through the throat of the exit-port, the construction of which tends to convert the velocity with 70 which the fluid passes through the throat into pressure in the expanding section beyond the throat leading to the discharge-conduit (not shown) from the pump. While the cross-section and area of the exit-port 75 may be changed to suit conditions of construction or the physical condition of the fluid to be pumped, the governing features to be observed for the best results are the area of the throat of the port with relation to the quantity of the fluid discharged, and the angle at which the port inclines downwardly from the pump-chamber. The rotating member, which I term a rotor in preference to an impeller, because it does not directly impel the fluid out of the exit-port but performs the sole function of revolving the fluid within the pump-chamber to set up and maintain centrifugal pressure in the annular space about the circle described by 80 the extremities of the revolving blade-tips, should be of slender construction to displace as little as possible of the fluid revolved in the pump-chamber, and offer the minimum of resistance to the fluid since, inasmuch as the rotor-blades revolve in a medium in which centrifugal force is maintained, the tangential stresses which the blades have to overcome are, at least mainly, those due to rotating the fluid passing 85 through the pump-chamber and to friction.

From the foregoing description of my pump, its distinguishing characteristics will be understood to be the following: Maintenance of centrifugal pressure in the pump-chamber on the body of fluid rotated therein about the circle described by the extremities of the revolving tips of the rotor which generates the centrifugal pressure; true circular guidance of this rotating fluid body, 100 and a volume thereof sufficiently large to render the radial outward movement of the fluid from the tips uniformly smooth; and automatic regulation of the quantity of fluid to be discharged from said body with 105 relation to variation in the head.

I realize that considerable variation is possible in the details of construction thus specifically shown and described, and I do not intend by illustrating a single, specific 110

or preferred embodiment of my invention to be limited thereto; my intention being in the following claims to claim protection upon all the novelty there may be in my invention as broadly as the state of the art will permit.

What I claim as new and desire to secure by Letters Patent is:—

1. A rotary pump comprising a casing provided with a completely circular internal periphery and a peripheral inclining exit-port provided with a throat at its inner end, and means coöperating with said port to produce and maintain outward radial and gradually diminishing flow of fluid in the pump-chamber and outward radial and gradually increasing pressure thereof in said chamber for discharging the fluid from the annular space adjacent to said periphery.
2. A rotary pump comprising a casing containing the pump-chamber having a completely circular internal periphery, an entrance-port and a peripheral inclining exit-port enlarging outwardly from an inner throat-section, and a rotor revolvably supported in the chamber to generate by revolving therein radial pressure of the fluid against which it operates and forming with said periphery about the circle in which the tip extremity of the rotor revolves, an annular space for fluid exposed to said radial pressure.
3. A rotary pump comprising a chamber having a completely circular internal periphery, a rotor having a diameter less than that of said periphery and supported to revolve concentrically within said chamber and forming an annular space between said periphery and the circle in which the tip-extremities of the rotor revolve, an entrance-port, and an exit-port connecting with said annular space and the area of which is less than the radial cross-sectional area of said annular space.
4. A rotary pump comprising a casing containing the pump-chamber having a completely circular internal periphery, an entrance-port and a peripheral inclining exit-port, and a light and slender radially-bladed rotor revolvably supported in the chamber to generate by revolving therein radial pressure of the fluid against which the blade operates and extending short of said periphery to form therewith about the circle in which the tip-extremity of the blade re-

volves, an annular space for fluid exposed to said radial pressure.

5. A rotary pump comprising a casing containing the pump-chamber having a completely circular internal periphery, a central entrance-port and peripheral inclining exit-port enlarging outwardly from an inner throat-section, a central shaft, and a radially bladed rotor in the casing on the shaft operating to generate radial pressure of the fluid which it revolves and extending short of said periphery to form therewith about the circle in which the tip-extremity of the rotor revolves an annular space for fluid exposed to said radial pressure. 70

6. A rotary pump comprising a casing containing the pump-chamber having a completely circular internal periphery, an entrance-port and a peripheral exit-port, and a rotor having radially-extending resilient blades and revolvably supported in the chamber to generate by revolving therein radial pressure of the fluid against which the blades operate and forming with said periphery about the circle in which the tip-extremities 80 of the blades revolve an annular space for fluid exposed to said radial pressure.

7. A rotary pump comprising a casing containing the pump-chamber having a completely circular internal periphery, an intake-port and a peripheral inclining exit-port enlarging outwardly from an inner throat-section, a rotor having a blade formed of resilient laminated metal sheets, the rotor being revolvably supported in the chamber to generate by revolving therein radial pressure of the fluid against which the blade operates and the blade forming with said periphery about the circle in which its tip-extremity revolves an annular 90 space for fluid exposed to said radial pressure.

8. In a rotary pump, a rotor rotatably supported in the pump-chamber and provided with resilient blades extending from the rotor-hub, the length of each blade being shorter in its section extending from the hub-periphery than the radial distance between the hub to the inner periphery of the pump-casing under all conditions in the 105 pump-chamber.
